UNITED STATES PATENT OFFICE.

HENRY FOERSTER, OF CHICAGO, ILLINOIS.

SASH-LOCK.

1,126,969.

Specification of Letters Patent.

Patented Feb. 2, 1915.

Application filed May 1, 1914. Serial No. 835,616.

To all whom it may concern:

Be it known that I, HENRY FOERSTER, citizen of the United States, residing at Chicago, in the county of Cook and State of Illinois, have invented certain new and useful Improvements in Sash-Locks; and I do hereby declare the following to be a full, clear, and exact description of the invention, such as will enable others skilled in the art to which it appertains to make and use the same.

This invention relates to improvements in sash locks and has for its object to provide a sash lock which will answer a plurality of purposes, namely, to lock sashes against relative opening movement, to limit the relative opening movement of said sashes, and to draw the meeting rails of the sashes toward each other during the locking operation.

The invention consists in the features of construction and combinations of parts hereinafter fully described and particularly claimed.

In the accompanying drawings illustrating the invention: Figure —1— is a fragmentary view of the meeting rail portions of the upper and lower sashes of a window equipped with a sash lock embodying my invention. Fig. —2— is a vertical transverse section on the line 2—2 of Fig. —1—. Fig. —3— is a top plan view of the meeting rails of the sashes equipped with a sash lock embodying my invention. Fig. —4— is a vertical section through the meeting rails of the sashes showing the same separated as when one or other of the sash is moved to open position, and shows the sash lock embodying my invention in elevation.

The particular objects of my invention are, first, to provide a sash lock which, besides affording an efficient lock to prevent relative opening movement of the sashes will, during the operation thereof, lock said sashes and draw the meeting rails thereof together to form an air-tight joint. A further object of the invention is to provide a sash lock equipped with a suitable means for limiting the relative opening movement of the sashes when the lock is disengaged, and which upon closure of the open sash or sashes will automatically lock said sashes against reopening without first manipulating the lock.

Other objects of the invention will ap-

pear from the following description of the same.

My said sash lock comprises a housing 1 mounted upon the upper rail 2 of the lower sash of a window, and which is provided with side flanges 3 through which the fastening screws 4 pass. Said housing is substantially semi-cylindrical along its top wall, and is provided in its end walls with openings through which the bolt or plunger 5 and its shank 6 are adapted to move longitudinally and rotatively; said openings being substantially concentric with the top wall of the housing. The shank 6 is of smaller diameter than the bolt or plunger 5 so that at the juncture of said parts an annular shoulder 7 is provided against which one end of the compression spring 8 bears, the latter bearing at its other end against the opposing end wall of the housing. The said spring 8 maintains the bolt or plunger 5 normally projected, the same being adapted to be drawn inwardly against the action of said spring 8 by means of the thumb piece 9 mounted upon the outer projecting end of the shank 6 and which during rotation engages a helical cam surface 10 constituting the outer edge of a helical flange 11 cast integral with the outer end wall of said housing 1 concentric with the opening through which the shank 6 passes.

The bolt or plunger 5 is provided at its outer end with a flange 12 which constitutes substantially an eccentric, that is to say, said flange is substantially annular and of larger diameter than the bolt or plunger 5 so as to be flush with the circumferential face of the latter at one point and project correspondingly farther outwardly therefrom at a diametrically opposite point.

Mounted upon the lower rail 13 of the upper sash is a socket member 14 adapted to be engaged by said bolt or plunger 5; said member comprising a base 15 perforated for the passage of screws 16 for mounting the same on the rail 13 and having an upwardly extending edge flange 17 along its rear edge and parallel with the pane of glass 18 mounted in said sash. The said flange 17 carries an overhanging flange 19 at its upper edge; the same having an inclined surface 20 and being provided with a recess 21 opposing the base 15 whereby a lip 22 is provided which is adapted to be engaged by the flange 12 of the bolt or plunger 5.

Side flanges integral with the base flange 15 and the side edges of the flange 17 serve to reinforce the structure.

The flange 12 of the bolt or plunger 5 projects farthest outwardly from the latter in a direction diametrically opposite to the direction of projection of the thumb piece 9 so that as the latter is turned while in engagement with the cam face 10 of the flange 11 the said flange 12 will pass upwardly into the recess 21 and into engagement with the lip 22, and as the rotary movement of the bolt or plunger is continued during engagement of said thumb piece 9 with the cam surface 10 the bolt or plunger will be drawn inwardly against the action of the spring 8 and will draw the said member 14 in the same direction, thus obviously causing the rails 2 and 13 to move toward each other. The said bolt or plunger 5 normally projects beyond the meeting face of the rail 2 and into the path of the upper rail of the upper sash (not shown) but may be withdrawn against the action of the spring 8 entirely out of the path of such upper rail by drawing the thumb piece outwardly against the action of said spring 8 until the flange 12 contacts with the overhanging flange 23 at the inner end of the upper wall of the housing, and by then turning the same through an arc of substantially one hundred and eighty degrees and drawing the same farther outwardly in the same direction and then turning the same back to the position shown in Fig. —2—, the said flange 12 will engage in the recess 24 between the lip 23 and the inner end wall of the housing 1 and will engage said lip to prevent return of the bolt or plunger 5 to the position shown in Figs. —2—, —3— and —4—.

Mounted upon the lower rail 13 of the upper sash laterally of the member 14 is a bearing member 25 having parallel vertical flanges 26 between which an arm 27 is pivotally mounted, said arm being provided with a small longitudinal slot 28 through which the pin 29 mounted in said flanges 26 passes. Said arm 27 may be of any desired length and is provided with a longitudinal slot 30 extending almost the entire length thereof, and through which the bolt or plunger 5 passes. Said bearing member 25 is so disposed as to cause said arm to swing between the member 14 and the housing 1. The said slot 30 in said arm is laterally enlarged as at 31, adjacent to its pivotal connection with the member 25 to permit the passage of the flange 12 therethrough so that said bolt or plunger 5 may be drawn into and out of engagement with said arm at will when the sash rails 2 and 13 are in opposed position as shown in Fig. —2—. In opening the window it is, of course, primarily necessary to turn the bolt or plunger 5 so

as to disengage the flange 12 from the lip 22 and then withdraw the said bolt or plunger so that the flange 12 lies between the lip 22 and the arm 27. During outward movement of the flange 12 the same will engage the opposing face of the arm 27. By now raising the lower sash or lowering the upper sash the bolt or plunger 5 will pass into a narrower portion of the slot 30 toward the free end of said arm 27 and when engaged with the outer end wall of said slot will limit the opening movement of the sash. The bolt or plunger 5 may, when the meeting rails 2 and 13 of the sashes are disposed in the position shown in Fig. —4—, occupy the position shown in the last-named figure, or in Fig. —2—. In either event the inclined surface 20 of the member 14 will lie in the path of the outer end of said bolt or plunger so that upon returning the sashes to relative closed position the same will be forced by said inclined surface 20 inwardly against the action of the spring 8 and will thus, if in the position shown in Fig. 4, pass the lip 22 and spring into engaging relation to the lower edge of said lip, thereby locking the sashes against reopening except by again manually moving the bolt or plunger against the action of said spring 8.

If it is desired to open the window wide or to a greater extent than permitted by the arm 27, the bolt or plunger is first turned to the position shown in Fig. —4—, and drawn outwardly until the flange 12 has passed the lip 22, after which it may be freely drawn farther outwardly in the same direction until said flange 12 has passed through the enlarged portion 31 of the slot 30 in said arm 27 and until the flange 12 strikes the inner end wall of the housing 1, whereupon it is returned to the position shown in dotted lines in Fig. —2—, leaving the said flange 12 in outward engagement with the lip 23. The window may be now opened wide and in the event that it is desired not to use the arm 27 the latter may obviously be turned to a position entirely out of the path of and out of engaging relation to said bolt or plunger 5.

It will be obvious from the foregoing that the lock may be used independently of or in conjunction with the arm 27 without affecting its efficiency as a lock. When used in conjunction with the arm 27 my device has the further advantage of limiting the opening movement of the sashes to an extent sufficient for purposes of ventilation, but insufficient to permit the passage through the opening of the body of a man.

I claim as my invention:

1. A sash-lock comprising a housing and a socket member mounted respectively on the meeting rails of two window sashes, a spring pressed plunger rotatably and reciprocably mounted in said housing and

- adapted to engage at one end in said socket member, a thumb-piece on the other end of said plunger, an external cam-surface on the housing adapted to be engaged by said thumb-piece for imparting longitudinal movement to said plunger against the action of said spring when rotated in one direction, an eccentric flange on the socket engaging end of said plunger, an overhanging lip 10 on the socket-member adapted to be engaged by said flange as said plunger is rotated in the direction aforesaid, and an overhanging lip on said housing for engaging said flange on said plunger when the latter 15 is moved longitudinally against the action of said spring to the outer limit of its movement said thumb-piece being thrown out of engaging relation to said cam surface as said plunger is moved to the outer limit of 20 its movement.
2. A sash lock comprising a housing and a socket member mounted on the respective meeting rails of two window sashes, a manually operable spring pressed plunger reciprocably mounted in said housing and adapted to engage in said socket member to lock the window sashes against relative movement, an arm pivotally mounted contiguous to said socket member on the rail carrying 25 the same and adapted to be swung in a plane between the opposing faces of said housing and said socket member, there being a longitudinal slot in said arm in which said plunger is adapted to engage to limit the 30 relative opening movement of said sashes, said slot in said arm laterally enlarged at one point to permit passage of said flanged end of said plunger therethrough, said plunger rotatable to cause said flange to register 35 with the enlarged portion of said slot for disengaging the plunger from said arm and the latter adapted to be swung out of engaged relation to said plunger when the latter is withdrawn from engagement in said 40 slot, said plunger adapted to engage in said socket member after said arm is disposed out of engaging relation to said plunger.
4. A sash lock comprising a housing and a socket member mounted on the respective meeting rails of two window sashes, a manually operable spring pressed plunger reciprocably mounted in said housing and adapted to engage in said socket member to lock the window sashes against relative movement, an arm pivotally mounted contiguous to said socket member on the rail carrying 45 the same and adapted to be swung in a plane between the opposing faces of said housing and said socket member, there being a longitudinal slot in said arm in which said plunger is adapted to engage to limit the 50 relative opening movement of said sashes, a flange at the socket engaging end of said plunger adapted to engage one face of said arm as said plunger is withdrawn from said socket for preventing the same from being 55 withdrawn from engagement with said arm.
4. A sash lock comprising a housing and a socket member mounted on the respective meeting rails of two window sashes, a manually operable spring pressed plunger reciprocably mounted in said housing and adapted to engage in said socket member to lock the window sashes against relative movement, an arm pivotally mounted contiguous to said socket member on the rail carrying 60 the same and adapted to be swung in a plane between the opposing faces of said housing and said socket member, there being a longitudinal slot in said arm in which said plunger is adapted to engage to limit the 65 relative opening movement of said sashes, said slot in said arm laterally enlarged at one point to permit passage of said flanged end of said plunger therethrough, said plunger rotatable to cause said flange to register 70 with the enlarged portion of said slot for disengaging the plunger from said arm and the latter adapted to be swung out of engaged relation to said plunger when the latter is withdrawn from engagement in said 75 slot, said plunger adapted to engage in said socket member after said arm is disposed out of engaging relation to said plunger.
- In testimony whereof I have signed my name in presence of two subscribing witnesses.

HENRY FOERSTER.
